UNITED STATES PATENT OFFICE.

STEPHEN J. BRUTOFSKI AND JOHN ARMSTRONG, OF SCRANTON, PENNSYLVANIA.

BASEBALL-GAME APPARATUS.

Application filed February 28, 1927. Serial No. 171,527.

The present invention relates to amusement devices, and has reference more particularly to a miniature base ball game, for indoor use, which will afford amusement and also necessitate the employment of skill, in playing the game, in exemplification of the playing of the modern game of baseball.

One of the important objects of the present invention is to provide a base ball game apparatus which comprises a playing field, arranged on a suitable board, said board having a plurality of pockets formed on the upper surface thereof at predetermined points, for receiving the ball, comprising the projectile, each pocket being designated for indicating the particular play, a manually actuated batter being provided for striking the ball and batting the same out into the playing field.

A further and salient object of the invention is to provide a base ball game apparatus wherein runners operate in suitable slots arranged adjacent the respective bases, means being provided for connecting the base runners with the batting member for effecting a movement of the runner toward the next base, in simulation of a base runner stealing a base, as the bat is swung rearwardly prior to the same completing its swing and striking the ball.

A still further object of the invention is to provide a base ball game apparatus of the above mentioned character, which is simple in construction, inexpensive to manufacture, and otherwise well adapted to the purpose for which it is designed.

Other objects and advantages of the invention will become apparent as the nature of the invention is better understood, and the same comprises the novel form, combination and arrangement of parts hereinafter more fully described, claimed, and shown in the accompanying drawings.

In the drawings wherein for the purpose of illustration is shown the preferred embodiment of our invention:

Figure 1 is a top plan view of the device embodying our invention.

Figure 2 is a transverse section, taken approximately on the line 2—2 of Figure 1, looking in the direction of the arrow.

Figure 3 is a fragmentary bottom plan view, showing the manner in which the base runners are operatively connected to the swinging bat.

Figure 4 is a detail sectional view showing the slot in the base tab and the vertically movable pin extending therethrough, as well as the guide means for the pin carrying member and the actuating cable connected thereto.

Figure 5 is a sectional view, through the boards showing the mounting for the swinging bat and the base runner controlling pin with which the swinging bat cooperates.

Figure 6 is a detail perspective view of one of the discs adapted to be placed on the upper end of the runner simulating pin and being indicative of a runner, and

Figure 7 is a detail perspective view of one of the plugs used in cooperation with the score board shown in Figure 2.

In the drawings, wherein like reference characters refer to like parts throughout the several views, the numeral 1 designates generally our improved base ball game apparatus, the same comprising a substantially rectangular board 2, constructed preferably of wood. Side walls 3 extend upwardly from the board 2 as well as do the end walls 4 and 5, respectively. In order that the board may be disposed at a slight incline when placed on a table or other suitable support, there is provided at the forward end of the board at the bottom thereof a rubber seat or button 6, such as is more clearly illustrated in Figure 2 of the drawings. As is also more clearly illustrated in this particular figure, the sides 3 are formed in their inner opposed faces with grooves 7 for receiving the respective side edges of the board 2 and in a like manner, the end walls are also provided with cooperating grooves. This will provide a rigid construction.

A baseball diamond is generally designated by the reference character 8, and is marked out on the upper surface of the board 2, adjacent the foremost end 5, and the various bases are indicated at 9, 10, and 11 respectively. The numeral 9 represents first base, the numeral 10 second base, and third base is indicated by the numeral 11. The numeral 12 indicates the home plate. The base paths which extend between the respective bases are designated at 13, with reference more particularly to Figure 1 of the drawings.

A groove 14 extends from the pitcher's box 15 to the home plate 12 and provides a means for delivering the ball to the swing-

ing bat, the construction of which will be hereinafter more fully described.

The projector comprises a block 16 from which projects laterally an arm shaped to simulate a bat. The bat is designated by the numeral 17. A pivot forming bolt 18 extends vertically through the board 2 at one side of the home plate 12 and through the block 16, whereby the projector will be adapted for co-operation with the ball moving forwardly in the groove 14 by gravity.

As is clearly illustrated in Figure 5, the block 16 is provided with a cavity, 19, in which is arranged a coil spring 20. This spring encircles the pivot bolt 18 and is secured at one end to the block 16, and its opposite end extends into the board 2. The purpose of the spring is to normally cause the bat 17 to be projected forwardly, and a forward swinging movement of the bat is limited by reason of the stop 21. The bat 17 is grasped by the person playing the game and is swung rearwardly so as to be disposed behind the home plate 12, in a manner as indicated by the dotted lines in Figure 1. It is so held in this position until the ball passes over the home plate, and then by releasing the bat, the spring 20 will cause the bat to strike the ball and to project the same away from the home plate onto the playing field, and the ball will fall into one of a series of pockets formed in the upper face of the board, and which pockets are designated by the numeral 22.

As is clearly illustrated in Figure 1, these pockets are arranged in a predetermined manner in the outfield, as well as adjacent the infield of the diamond 8. Each pocket may be marked by a number or other suitable indicia indicative of a particular play which occurs in the playing of the game, as for example, one pocket may indicate that the batter flied out to the center fielder, another pocket may indicate that the batter grounded out to an infielder, or that he made a safe base hit, etc.

A back board or strip 23 is arranged on the playing board 2 adjacent the rear end wall 4 and the forward edge of this strip is curved, thus providing means whereby the ball may be deflected back onto the playing field, should the same strike this strip when projected by the bat 17. Also arranged on the playing field at predetermined positions are suitable rubber abutments designated at 24, and the same provide a means whereby to deflect the ball should the same strike such abutments. For the purpose of clarification, the ball is designated by the letter A.

A particular space designated at 25, is arranged on the board to designate the hitting of a home run by a batter, and it is of course understood that this space is so arranged on the board as to make it difficult for the batter to place the ball therein. Additional abutments 26, similar to the abut-

ments 24 are arranged on the board for co-operation with the space 25, as is clearly shown in Figure 1.

For the purpose of further aiding in the deflection of the ball A during its flight or travel over the playing field, there is arranged on the inner opposed faces of the sides 3, the wooden strips 27, the inner edges of which are rounded. The bottom of each of these deflecting strips engages the upper face of the playing board 2.

A strip 28 is arranged at the forward end of the board 2, and formed in the outer longitudinal edge of this strip are a series of pockets 29, each of which may be indicative of a certain play incident to the playing of the base ball game, such as, for example, a strike or a ball. The purpose of these pockets, 29, in addition to the pockets 22 is to provide a means whereby should the ball A fail to enter any one of the aforementioned pockets 22, the same will by gravity move forwardly on the board and will finally enter one of the pockets 29, thus assuring a particular play every time the ball is batted by the person actuating the swinging bat 17.

In order that the players can keep an accurate account of the balls and strikes, as well as the outs and runs, we provide a score board 30, which may be mounted either on the upper edge of the rear end wall 4 or one of the side walls 3, in any particular manner. The board is provided with a series of holes 31, which are indicative of strikes, three of such holes being formed in the score board. The score board is also provided with additional holes 32 representing the number of balls thrown to the batter, four of such holes being provided. Also, a series of holes, represented at 33, are provided, for designating the outs, and the holes 34 represent the runs that are scored in a particular inning. A plug or pin, such as is shown at 35, in Figure 7, is formed with a reduced shank 36, whereby the same may be fitted in any one of the aforementioned holes, and as many of these plugs are employed as are necessary for designating the particular score or account of the balls and strikes, as well as the outs and runs scored.

In order that the complete score may be kept inning by inning the score board is formed at its upper portion with a pair of longitudinally extending channels 37, in which are slidable suitable strips designating the names of the particular teams playing the game, as well as individual strips having printed thereon the number of runs scored in each inning. It is of course, understood that the score board above the channels are marked off into innings and this is clearly illustrated in Figure 2.

The base paths 13 are formed with elongated slots 38 in advance of each of the bases, as is clearly shown in Figure 1, and operable within each slot is a base runner

carrying pin 39. The lower end of each pin is secured in a suitable plate 49, arranged beneath the board 2 and a channeled guide 41 is provided for each plate 40, in the manner as clearly illustrated in Figures 3 and 4. The upper end of each pin 39 projects above the upper surface of the board 2 and adapted to be detachably mounted thereon is the disc 42 shown in Figure 6, and which disc is in simulation of a base runner.

The discs 42 represent players and are only placed on the particular pins as the player reaches the particular base.

The several base runner carrying pins 39 are interconnected by a suitable cable 43, which extends through the respective guide channels 41 and also around guide pins 44 arranged therefor on the bottom of the board 2. A coil spring 45 is secured to one end of this cable, the other end of the spring being attached to the bottom of the board, and the purpose of this spring is to normally maintain the pins in the ends of the respective slots adjacent the respective bases.

The other end of the cable 43 is secured to the outer free end of an arm 46, which is pivoted at its inner end on the pivot bolt 18 provided for the batting mechanism, as is clearly shown in Figure 5, and carried by this arm 46 is a master pin 47, which projects upwardly through an arcuate shaped slot 48, provided therefor in the playing board 2, adjacent the block 16, and this pin projects a suitable distance above the board, so as to be within the path of the rearward movement of the swinging bat 17, as is also clearly disclosed in Figure 5.

Manifestly, when the bat 17 is moved in the direction of the arrow, the same will engage the master pin 47, and will move the same forwardly through the arcuate shaped slot 48, and as this pin moves in the particular slot provided therefor, the pivoted arm 46, will be actuated to simultaneously actuate all of the base runner carrying pins 39, for advancing the same forwardly in their respective slots to simulate the base runners attempting to steal the next adjacent base.

The movement of the base runner carrying pin will simulate the runners moving away from their respective bags or bases as the batter is about to swing at the next pitched ball. As heretofore stated, the base runner simulating discs 42 are placed on the upper ends of the base runner carrying pins 39, as the particular bases become occupied with players. As soon as one of the players or base runners is put out or scores a run, that particular base runner is removed from its respective pin.

It is believed from the foregoing description that the playing of the game is fully

understood, and therefore a further detailed description is thought unnecessary.

It will thus be seen from the foregoing description that we have provided a novel, yet simple game apparatus, which will exemplify the playing of a real base ball game, including all of its fine and technical points, and this apparatus will not only afford amusement, but will also necessitate the employment of an appreciable amount of skill in order to win the game.

While we have shown the preferred embodiment of our invention, it is to be understood that various changes in the shape, size, and arrangement of parts may be resorted to, without departing from the spirit or scope of the invention.

What we claim is:

1. In a game apparatus, the combination of a board having a representation of a base ball diamond thereon, a ball, a manually actuated bat for striking and projecting the ball on the playing field, base runner simulating means arranged in the base paths adjacent the respective bases of the diamond, and additional means controlled by the actuation of the bat prior to the same striking the ball for moving the first mentioned means along the base paths to simulate the runners advancing to the next base.

2. In a game apparatus, the combination of a board having a representation of a base ball diamond thereon, a ball, a manually actuated bat for striking and projecting the ball on the playing field, base runner simulating means arranged in the base paths adjacent the respective bases of the diamond, additional means controlled by the actuation of the bat prior to the same striking the ball for moving the first mentioned means along the base paths to simulate the runners advancing to the next base, and means for returning the movable elements to their normal positions upon the completion of the swinging movement of the bat.

3. In a game apparatus, the combination of a board having the representation of a base ball diamond thereon, a ball, a manually actuated spring controlled pivoted bat for striking and projecting the ball onto the playing field, the base paths being slotted adjacent the respective bases, base runner carrying pins projecting upwardly through the slots, means for interconnecting the several pins, and additional means connected to the pins and actuated by the swinging movement of the bat prior to the same striking the ball for moving the pins along in the respective slots to simulate the base runners advancing to the next respective bases.

4. In a game apparatus, the combination of a board having the representation of a base ball diamond thereon, a ball, a manually actuated spring controlled pivoted bat for striking and projecting the ball onto the

playing field, the base paths being slotted adjacent the respective bases, base runner carrying pins projecting upwardly through the slots, means for interconnecting the several pins, and additional means connected to the pins and actuated by the swinging movement of the bat prior to the same striking the ball for moving the pins along in the respective slots to simulate the base runners advancing to the next respective bases, said last mentioned means comprising a pivoted arm arranged on the board and connected at its free end to the aforementioned pins, a master pin projecting upwardly from said arm, and disposed within the path of movement of the swinging bat.

5. In a game apparatus, the combination of a board having a representation of a base ball diamond thereon, a ball; a manually actuated spring controlled bat adapted for swinging movement on the upper face of the board, the base paths being provided with vertical slots adjacent the respective bases, a plate arranged beneath each slot, a base runner carrying pin projecting upwardly from each plate through the respective slot,

guide means for each plate, an arm pivoted at one end on the bottom of the board below the swinging bat, a master pin projecting upwardly from said arm, said board being provided with an arcuate slot through which the master pin projects, said master pin being disposed in the path of movement of said bat, a flexible connection between the free end of said arm and the series of base runner carrying pins whereby the same are adapted for simultaneous actuation, said base runner carrying pins adapted to move along in the respective slots when the bat is swung rearwardly into engagement with the master pin for moving the same in its slot prior to the bat striking the ball to simulate the runners advancing to the next base, and means for returning the base runner carrying pins to their normal positions when the bat is moved out of engagement with the master pin.

In testimony whereof we affix our signatures.

STEPHEN J. BRUTOFSKI.
JOHN ARMSTRONG.
